United States Patent Office

Des. 195,952
Patented Aug. 13, 1963

195,952

SHAVER

Norman Thomas Sanders, Mappleborough Green, Studley, England, assignor to Needle Industries Limited, Birmingham, England, a British company

Filed July 25, 1962, Ser. No. 71,042

Term of patent 14 years

(Cl. D22—3)

FIGURE 1 is a front perspective view of a shaver showing my new design.

FIGURE 2 is a rear perspective view thereof.

FIGURE 3 is an elevational view of the side opposite to that shown in FIGURE 1; and

FIGURE 4 is a top plan view thereof.

I claim:

The ornamental design for a shaver substantially as shown.
